UNITED STATES PATENT OFFICE.

ROBERT REACH, OF PHILADELPHIA, PENNSYLVANIA.

DESIGN FOR A ROLLER-SKATE FRAME.

SPECIFICATION forming part of Design No. 28,447, dated April 5, 1898.

Application filed December 22, 1897. Serial No. 663,107. Term of patent 7 years.

To all whom it may concern:

Be it known that I, ROBERT REACH, a citizen of the United States, residing in the city and county of Philadelphia, State of Pennsylvania, have invented and produced a new and original Design for a Roller-Skate Frame, of which the following is a specification.

In the accompanying drawings, Figure 1 is a side elevation. Fig. 2 is a bottom plan, 10 and Fig. 3 is a front view.

The leading features of my design consist in a skate-frame comprising a horizontal base-plate with parallel frames extending therefrom, separated from each other, said frames 15 including horizontal portions and vertical

portions between the horizontal parts and the base-plate of the skate.

In the drawings the base-plate is shown at *a*, the vertical portions at *b*, and the horizontal parts at *c*.

What I claim is—

The design for a roller-skate frame herein shown and described.

In testimony whereof I affix my signature in presence of two witnesses.

ROBERT REACH.
